INVENTOR,

Jules Pernot,
By
John Stewart,
ATTORNEY.

UNITED STATES PATENT OFFICE.

JULES PERNOT, OF PATERSON, NEW JERSEY.

BOX MOTION FOR LOOMS.

Application filed August 31, 1927. Serial No. 216,568.

This invention relates to looms in which the shifting of the boxes for the shuttles is effected by moving the mechanism for causing such shifting into position to be actuated by going means in the loom, as when said mechanism includes a vibrator-gear journaled in a vibrator-lever between two mutilated cylinder-gears of the going means and is adapted to be shifted with the vibrator-lever into mesh with the cylinder-gears alternately; see, for example, the Wattie and Hutchins Patent No. 551,104. Usually the movements of said mechanism depend on a dobby. Where the loom contains a jacquard machine it is desired to make such movements depend on the call of hooks in that machine. But heretofore this has not been accomplished without certain troublesome complications. According to the present invention the selection or calling is effected from pattern-controlled hooks or equivalent of a jacquard machine (or it may be a dobby), whereas the actual movements of the vibrator mechanism are effected by an actuator operated by going means in the loom. This in itself is not new. But it is new and is a feature of my invention that the actuator transmits the movement from the going means to the vibrator mechanism directly and not through means movable independently of the latter.

In the drawing,

Fig. 1 is a side elevation of a loom embodying the invention; Figs. 2 and 3 are a rear and side elevation, respectively, of certain of the principal parts of the invention on a larger scale; and

Fig. 4 is a fragmentary rear elevation of a detail.

The loom frame 1; lifter-rod 2 for the boxes 3; the lever 4 to which the lifter-rod is connected; the bell-crank levers 5 fulcrumed in the loom-frame and connected by links 6 to different points in the length of and thus supporting lever 4; the vibrator-gear connectors 7; the vibrator-gears 8 to an eccentric point of each of which one such connector is pivoted and each of which is journaled in a vibrator-lever 9 fulcrumed in the frame; the mutilated cylinder gears 10 formed with gears 10^a and forming a part of a gear-train including the transmission gears 11 and 12; the gear 13 from which such train is driven; and the detent device 14 controlled by a cam 15 and serving to lock a vibrator-lever in either position to which it is shifted (with its vibrator-gear in mesh with or operative

relation to one or the other of the cylinder gears) are or may be all the same as usual.

The vibrator mechanism movable to be actuated by the going means is here made to include, with each system of parts 7, 8 and 9, an upstanding member (incidentally forming a guide) 16 connected to lever 9 and which, if it is a wire or otherwise flexible, may be held taut by a lever 17 weighted at 17^a but not so as to balance or overbalance lever 9; said member has affixed to it a block 18 in which is pivoted a catch-device 19 or bell-crank lever formed with a notch 19^a in its depending arm.

The aforesaid going means is here afforded by the train of parts 10, 10^a, 11, 12 and 13. When the vibrator mechanism is moved up or down, so that gear 8 meshes with upper or lower gear 10, said mechanism is actuated by the going means, i. e., gear 8 is turned one way or the other to shift the box structure and comes to a dwell, all in a characteristic way and well known; in the present case this moving of said mechanism in the upward direction depends on upward movement of its member 16, its downward movement being due to allowing member 16 to fall and to the action of gravity on said mechanism.

Sliding on member 16 as a guide is an actuator comprising a block 20 having a projection or toe 20^a to engage in notch 19^a of the catch-device and a link 22 connecting the block with a wrist-pin 21 which is set close to the axis of one of the gears in the gear-train, as 12.

The catch-device is pattern-controlled, as by being connected to a lever structure, generally denoted by 23 and fulcrumed at the top of the loom frame, by a link 24, which lever structure is in turn connected, by a link 25, with one of the hooks 26 of a jacquard machine, whose rising and falling grid is shown at 27. Each lever structure here comprises a shaft 23^a and cranks 23^b, 23^c thereon to which the links 25 and 24 are respectively connected. A spring 28 coiled around the shaft and attached at its ends to the shaft and a part of the loom frame normally turns the shaft in the direction to hold the catch-device retracted.

There is need for but one actuator for as many of said vibrator mechanisms and corresponding catch-devices as the loom may require: see Fig. 2, which shows four of the members 16 and of certain of the other parts, two of which appertain to the lever 4 for the

boxes at the near side of the loom and the other two of which appertain to such a lever (not shown) as 4 for the boxes at the other side.

5 Operation: While the going means is operating the actuator will be constantly reciprocated. Assuming any one of said vibrator mechanisms to be in either of its positions for actuation by one of the cylinder-gears, on each 10 rotation of the mentioned gear-train detent 14 moves to unlock lever 9 and permit said mechanism to shift to its other position. If said mechanism has been positioned for actuation by the lower cylinder-gear and a "call" comes 15 from the corresponding hook 26 for it to be moved to position for actuation by the upper cylinder-gear the catch-device will couple said mechanism with the actuator on the latter's next ensuing rise and said mechanism 20 (being unlocked for the purpose, as stated) will shift to the upper position. It will remain, effectively, in that position until the hook 26 allows the catch-device to retract or assume the uncoupling position; that is to say 25 (assuming said mechanism is to remain now unactuated for more than one rotation of the cylinder-gears), whereas it will of course fall each time the detent moves to unlocking position, it will be at once returned by the actuator and (until the teeth of the cylinder-gears have swept past) stand locked by the 30 detent in the upper position. In short, the vibrator mechanism functions the same as it does in all box-motions characterized by such 35 a mechanism except that when the vibrator mechanism is to remain operative with respect to the upper cylinder-gear for more than one pick of the loom it falls to the lower position and is returned to the upper position in the 40 intervals between those periods in the cycle of rotation of the cylinder-gears when their teeth are presented to, or sweeping past, the vibrator-gear.

45 In my construction the catch-device acts to transmit movement from the actuator to the vibrator-mechanism directly; in any previous box operating system of which I know and in which the selection is accomplished from the jacquard machine of the loom and 50 the shifting effected by going means a catch-device has shifted a means (as in an "indicator") movable step by step to obtain the two

positions of said mechanism, which means was thus an intermediary between the catch-device and the (reciprocatory) vibratory 55 mechanism.

I claim:

1. In a shuttle-box motion for looms, the combination, with going means including spaced mutilated gears and with vibrator 60 mechanism movable back and forth from one to the other gear to be actuated thereby and normally urged toward one gear, of a constantly going actuator moved back and forth by the going means and from which to move 65 said mechanism toward the other gear, and a pattern-controlled catch-device movable into and out of position to transmit such movement from the actuator directly to said mechanism on movement of said actuator in one direction and carried by one of them.

2. In a shuttle-box motion for looms, the combination, with going means including spaced mutilated gears and with vibrator mechanism movable back and forth from one 75 to the other gear to be actuated thereby and normally urged toward one gear and having a guide, of a constantly going actuator moved back and forth by the going means and guided by said guide and from which to move 80 said mechanism toward the other gear, and a pattern-controlled catch-device movable into and out of position to transmit such movement from the actuator directly to said mechanism on movement of said actuator in one 85 direction.

3. In a shuttle-box motion for looms, the combination, with going means including spaced upper and lower mutilated gears and with vibrator mechanism movable up and 90 down from one to the other gear to be actuated thereby and normally urged downward and having an upstanding flexible guide movable up and down therewith and means to hold the guide taut, of a constantly going actuator 95 moved back and forth by the going means and guided by said guide and from which to move said mechanism upward, and a pattern-controlled catch-device movable into and out of position to transmit such movement from the actuator to said mechanism on movement of said actuator in one direction.

In testimony whereof I affix my signature.
JULES PERNOT.
